UNITED STATES PATENT OFFICE.

EDWARD L. CUMMINGS, OF WATERFORD, NEW YORK, ASSIGNOR TO PUTNAM KNITTING COMPANY, OF COHOES, NEW YORK, A CORPORATION OF NEW YORK.

SINKER MECHANISM FOR KNITTING-MACHINES.

1,334,597.

Specification of Letters Patent. Patented Mar. 23, 1920.

Application filed September 11, 1919. Serial No. 323,116.

To all whom it may concern:

Be it known that I, EDWARD L. CUMMINGS, a citizen of the United States, residing at Waterford, in the county of Saratoga and State of New York, have invented new and useful Improvements in Sinker Mechanism for Knitting-Machines, of which the following is a specification.

Reference may be had to the accompanying drawings, and the reference characters marked thereon, which form a part of this specification. Similar characters refer to similar parts in the several figures therein.

This invention relates to an improvement upon United States Letters Patent No. 416,256, granted to George W. Cummings, December 3, 1889, for a plush bur for knitting-machines.

Burs of the character shown and described in said Letters Patent are adapted for use in incorporating in a knitted web of fabric a backing-thread having loops exposed on the surface of the web for various purposes.

In the manufacture of certain fabrics the loops formed upon the surface of the knitted web by means of these burs, are brushed to form a plush surface, and the bur shown in said Letters Patent was adapted to form loops of the backing-thread or yarn, of sufficient prominence to give the proper plush surface to the fabric when brushed.

In the use of said prior bur, however, the sinker-fingers, whereby the loops of the backing-thread were formed, were forced inwardly to form the loops by engagement of certain of the knitting-needles with the respective sinker-fingers. This not only caused a strain upon the needles but limited the length of the loop which could be formed.

In the manufacture of certain knitted fabrics for toweling, wash-cloths and the like, it is desirable to produce upon the surface of the knitted web, numerous loops of thread similar in appearance to, and accomplishing the same purpose as, the loops on woven fabric commonly known as Turkish toweling. Such loops have to be made of much more prominence than the loops which are to be brushed in making the plush surface, and it is found difficult to produce loops of sufficient prominence for the present purpose by the use of said prior patented

bur, and it has been found necessary to provide means independent of the needles for positively moving the sinker-fingers inwardly and outwardly in forming the loops. 55

The principal object of the present invention is to provide a more simple and accessible mechanism for thus positively moving the sinker-fingers inwardly and outwardly. 60

Other objects will appear in connection with the following description.

Figure 1 of the drawings is a top plan view of my improved sinker-mechanism showing its position relatively to the needles 65 of a circular spring-needle knitting-machine.

Fig. 2 is a bottom plan view of the sinker-mechanism.

Fig. 3 is a view in end elevation of the same as seen from the left-hand side of 70 Fig. 2.

Fig. 4 is a vertical cross-section of the same taken on the broken line 4—4 in Fig. 2.

Fig. 5 is a plan view of the ring which forms the pivot for the sinker-fingers. 75

Fig. 6 is a view in side elevation of the hub of the sinker-wheel.

Fig. 7 is a central longitudinal section of the same taken on the broken line 7—7 in Fig. 6. 80

Fig. 8 is a top plan view of the same.

Fig. 9 is a top plan view of the blade-carrying annulus.

Fig. 10 is a view of the same partly in side elevation and partly in vertical section 85 taken on the broken line 10—10 in Fig. 9.

Fig. 11 is a view in perspective of one of the sinker-wheel blades.

Fig. 12 is a view in side elevation of one of the sinker-fingers. 90

Referring to the drawings wherein the invention is shown in preferred form, 1 is a stationary support or bracket, mounted adjacent to the cylinder, 2, of a spring-needle circular knitting-machine having the usual 95 spring-needles, 3.

A support, 4, projects upwardly from the inner end of the support or bracket, 1, forming a means for rotatively mounting the rotary members of the sinker-mechanism in 100 proper relation to the knitting-needles.

Upon the support, 4, is rotatively mounted the hub, 5, of the sinker-wheel.

The sinker-wheel has the usual blades, 6,

each provided with a yarn-receiving-and-guiding notch, 7.

For certain purposes of the invention, the blades may be mounted in the wheel in any known manner. I have shown them mounted in the wheel by means of an annulus, 8, formed with the usual peripheral oblique slots or grooves, 9, adapted to receive the respective blades, 6, and provided with slotted apertures, 10, extending inwardly from the bottoms of said grooves, 9, and severally adapted to receive the dove-tailed shanks, 11, on the respective blades, 6.

The annulus, 8, is formed with a bottom opening, 12, adapted to receive and fit a cylindrical shoulder, 13, formed on the hub, 5, the upper surface of which shoulder is inwardly and downwardly beveled at 14, to correspond with the bevel on the underside of the respective shanks, 11, of the blades, which shanks are confined between said beveled surface, 14, and the top wall of the annulus, 8, as shown in Fig. 4.

A nut, 15, fitting the upper screw-threaded portion, 16, of the hub, 5, when screwed down tightly against the annulus, 8, serves to securely clamp the shanks of the blades between the beveled surface, 14, on the hub, and the top wall of the annulus, and causes the annulus and blades to rotate in unison with the hub.

Each of the blades, 6, is formed with a leg, 17, depending from the body of the blade along the outer surface of the hub, 5, and the depending legs of the blades are severally formed with a notch, 18, in their edge adjacent to the hub, said notches, 18, being adapted to receive and support in position a pivot-ring, 19, extending circumferentially of the hub.

This pivot-ring, 19, forms a support and pivotal connection for the sinker-fingers, 20, each of which is formed preferably of wire, and with a loop, 21, adapted to interlockably receive the pivot-ring, 19, and to rock thereupon.

Each sinker-finger, 20, is thus rockably mounted between two neighboring blades, 6, of the sinker-wheel with its upper end, 20^a, projecting upwardly above the pivot-ring, 19, and its lower end, 20^b, projecting downwardly below said ring.

The upper ends of the sinker-fingers are thus adapted to play inwardly and outwardly between the body portions of the neighboring blades in performing the well known function of forcing loops of the backing-yarn deeply in between the blades so as to produce prominent loops on the surface of the knitted fabric.

A cam, 22, mounted in fixed position upon the bracket, 1, engages on their outer side the upper ends, 20^a, of the successive sinker-fingers as the sinker-wheel is rotated, said cam being so formed as to force the upper

ends of the sinker-fingers as deeply as may be desired into the spaces between neighboring blades, 6.

A cam, 23, mounted in fixed position upon the bracket, 1, engages on their outer sides the lower ends, 20^b, of the successive sinker-fingers as the sinker-wheel is rotated, said cam being so formed as to force the lower ends of the sinker-fingers inwardly thereby causing their outer ends to be forced outwardly.

By the construction shown herein, one cam engages the sinker-fingers above their axis of rocking movement and the other cam engages the sinker-fingers below their axis of rocking movement, I am able to positively actuate the fingers both inwardly and outwardly by means of cams located exteriorly of the sinker-wheel whereby they are readily accessible for replacement and adjustment when desired.

The operation of the device is as follows:

The sinker-wheel being mounted as shown in Fig. 1 in position to mesh with the needles, 3, of the circular knitting-machine will be rotated by the rotary movement of the needle-carrying cylinder, 2, of the machine.

The cam, 22, is so located that it engages the outer side of the upper ends of the sinker-fingers to force them into the respective spaces between the blades in the sinker-wheel just in advance of the respective needles, causing the upper end of each sinker-finger to engage the thread or yarn and force a loop of the same into a needle-engaged space between two neighboring blades in the wheel.

Where the thread is not thus engaged and looped by the sinker-fingers, it is laid along the inner side or back of the needles in the usual manner to incorporate the backing-thread or yarn into the body of the knitted web.

By properly proportioning the sinker-fingers and the cam, 22, the sinker-fingers can be thus forced inwardly to any desired extent independently of the knitting needles, thus making it possible to produce loops of the backing-thread of desired length without respect to the depth to which the knitting-needles enter between the blades of the wheel.

I have shown and described the wheel whereby the thread or yarn is fed into the machine as a structure built up of several parts including the hub, blades, and means for mounting the blades upon the hub; but for certain purposes of the invention, the wheel may be constructed in any known manner whereby it is provided with spaces for engagement with the knitting-needles and sinker-fingers, and whereby it is adapted to properly feed the yarn into the machine.

While I have shown the sinker-fingers rockably mounted upon the wheel by means of the pivot-ring, 19, for certain purposes of the invention, the fingers may be rockably mounted upon the wheel in any known manner at a point between their upper and lower ends whereby they can be engaged by the respective cams at a point above and at a point below their axis of rocking movement.

The sinker-wheel is retained upon the spindle, 4, by means of a nut, 23, and a lock-nut, 24, fitting a reduced screw-threaded end-portion, 25, of the spindle.

A dust-cap, 26, fits over the nut, 15, protecting the nuts, 23, 24 and 15, and the outer end of the spindle from dust and lint.

What I claim as new and desire to secure by Letters Patent is:

1. A thread-feeding sinker-wheel provided with spaces for engagement with knitting-needles, and having sinker-fingers each rockably mounted at a point between its ends with the upper ends of the fingers in position to play in certain of said needle-engaging spaces, said fingers being exposed both above and below their axis of rocking movement for engagement by suitable actuating mechanism.

2. Sinker-mechanism for knitting-machines having a rotatively mounted thread-feeding wheel provided with spaces for engagement with the knitting-needles, sinker-fingers rockably mounted at a point between their ends upon said wheel in position for the upper ends of the fingers to play in certain of the needle-engaging spaces in said wheel, and a pair of cams mounted exteriorly of said wheel, one engageable with the upper ends of the sinker-fingers above their axis of rocking movement, and the other engageable with the lower ends of the sinker-fingers below their axis of rocking movement.

3. Sinker-mechanism for knitting-machines having in combination a supporting bracket, a spindle carried by said bracket, a thread-feeding wheel rotatively mounted upon said spindle and provided with spaces for engagement with the knitting-needles, sinker-fingers rockably mounted at a point between their ends upon said wheel, and a pair of cams removably mounted upon said bracket, one engageable with the upper ends

of the sinker-fingers above their axis of rocking movement, and the other engageable with the lower ends of the sinker-fingers below their axis of rocking movement.

4. Sinker-mechanism for knitting-machines having in combination a sinker-wheel, 60 a hub, thread-feeding blades mounted upon said hub with intervening spaces for engagement with the knitting-needles, said blades having downward extensions notched on their inner side, a pivot-ring supported in 65 the notches in said downward extensions extending circumferentially of the hub, sinker-fingers each provided with a loop between its ends interlockably rockably mounted upon said pivot-ring with the upper ends of said 70 fingers in position to play in certain of said needle-engaging spaces, and a pair of external cams, one engageable with the upper ends of the sinker-fingers above their axis of rocking movement, and the other engageable 75 with the lower ends of the sinker-fingers below their axis of rocking movement.

5. A sinker-wheel having a hub formed with a cylindrical shoulder, the upper surface of which is inwardly and downwardly 80 beveled, an annulus surrounding said shoulder provided in its periphery with blade-receiving grooves and with inwardly extending slots, blades mounted in the respective peripheral grooves in said annulus with 85 intervening needle-engaging spaces, and having dove-tailed shanks extending through said inwardly extending slots, said blades having downward extensions notched on their inner sides, the shanks of said blades 90 being confined between the top of said annulus and said beveled surface on said shoulder, and a nut screwed upon the upper end of said hub into clamping engagement with said annulus, a pivot-ring mounted in the 95 notches in said downward extensions of the blades circumferentially of the hub, and sinker-fingers each provided between its ends with a loop interlockably rockably mounted upon said pivot-ring with the upper ends of 100 said fingers in position to play in certain of said needle-engaging spaces, said fingers being exposed both above and below their axis of rocking movement for engagement by suitable actuating mechanism.

In testimony whereof I have hereunto set my hand this 22nd day of May, 1919.

EDWARD L. CUMMINGS.
